TYPEWRITING MACHINE

Dothan L. Shelton, Amarillo, Tex., and Gurst T. Shelton, Bradley, Ark.

Application December 8, 1931. Serial No. 579,811

14 Claims. (Cl. 197—25)

This invention relates to typewriting machines having means for actuating type bars and has for its object to provide an electrically operated typewriter that is automatic in its operation and so designed that it can be operated by finger movements at a speed in keeping with the spoken word. This is accomplished through novel means embodying a keyboard comprised of finger keys adapted to be operated either singly or in combinations for the purpose of registering in the machine single letters or combinations of letters comprising entire words or syllables, a selector mechanism cooperating with finger keys for the purpose of selecting letters or combinations of letters to be written, a releasing mechanism on which is registered the results of selector mechanism and which in turn imparts type selections to type bar actuating means for writing the letters or letter combinations selected, a timing means for causing selected type bars to operate in a consecutive order, a type basket comprised of two independent units adapted to cooperate in such way that two type bars may be thrown into printing position simultaneously, a series of reciprocating type bars arcuately arrayed in two independent units and radiating from two independent writing centers, and power means for actuating type bars.

In the drawings:

Figure 1 is a sectional side elevation of a typewriting machine embodying the invention, showing internal construction.

Figure 2 is a plan view showing the keyboard and the order of arrangement of finger keys with a sectional view of type basket, showing the arrangement of type bars, the division of type basket, the type basket spacing mechanism, and other related parts.

Figure 3 is a side elevation of certain essential mechanisms, the frame and some of the mechanism of machine being omitted for the purpose of better illustration.

Figure 4 is a front elevation of keyboard.

Figure 5 is a plan view of medial letter finger keys and corresponding selector mechanism.

Figure 6 is a side elevation of same.

Figure 7 is a distended oblique view of selector mechanism shown in Figures 5 and 6.

Figure 8 is a rear sectional view showing position of electric drive motor and means for driving power roller and release rotor, with one-round clutch and gear train.

Figure 9 is a sectional view of one-round clutch.

Figure 10 is a view of clutch throwout lever showing cam face and detent.

Figure 11 is an isometric projection of a section of timer ball race with interlocking balls and timer plungers.

Figure 12 is an oblique projection of release rotor, timer plungers, and letter spacing mechanism.

Figure 13 is a view of left timer plunger and auxiliary plunger.

Figure 14 is a view of cylindrical section of release rotor showing slidable registering member and spring detent.

Figure 15 is an oblique projection of type bar actuating cam.

Figure 16 is an elevational view of timer plunger after it has been tripped by release rotor showing position of related parts.

Figure 17 is an elevational view of type bar actuating mechanism showing type bar in operated position.

Figure 18 is a plan view showing the relative position of type basket to platen, and type guides for right and left segments of type basket.

Figure 19 is a plan view showing position of type guides when movable segment of type basket is in spaced position.

Figure 20 is a front elevation of the same.

Figure 21 is a sectional view of the type basket spacing mechanism and the platen positioning mechanism.

Figure 22 is an end view of certain essential parts of type basket spacing mechanism.

Figure 23 is a rearward elevation showing detailed construction of type basket spacing mechanism.

Figure 24 is an oblique projection of same showing structural details of certain parts.

Figures 25, 26, 27, and 28 show normal and actuated views of platen positioning mechanism.

Referring to the drawings, there is disclosed a machine frame A, carriage B supporting the usual platen C, an electric motor D with the usual circuit and switch E for closing and opening circuit. All these parts as well as the various other instrumentalities of the machine such as the capital shift, tabulating mechanism, carriage drive and return mechanism, line feed, ribbon oscillator, and other essential parts common to typewriting machines may be of any conventional or desired construction.

By referring to Figure 2 it will be observed that the keyboard consists of forty-four finger keys, designated by the numeral 4, eight of which are function keys and thirty-six of which are type keys.

The finger keys are arranged in both transverse

- and longitudinal rows lying in three horizontal planes (see Figures 1, 2, and 4), the main body of the keyboard lying in the intermediate plane and having centrally located therein a space function key extending across the two central transverse rows. The keys immediately to the right and left of space key are placed in very close proximity thereto so that space key and letter keys may be depressed simultaneously with one finger, the finger being placed over the division between the keys and resting on both keys. The keys in longitudinal rows are placed in very close proximity to each other to facilitate the fingering of two keys simultaneously with one finger in the manner above explained.
- The function keys serve to control the functions of letter spacing, tabulating, carriage return, capital shift, line space, back space, etc. The letter keys serve to control the operation of seventy-one bars more or less. Of the letter keys thirteen are used in writing numerals, figures, and punctuation marks, the remaining twenty-three being used in writing the letters of the alphabet.
- The keys marked A, S, P, T, W, H, N, R, which are to the left of the space key and lie in the same horizontal plane are initial letter keys, they being used singly and in combinations to control the operation of type bars writing the initial letters.
- The keys marked R, B, L, N, D, G, S, T, E, Y, which are to the right of the space key and lie in the same horizontal plane are known as final letter keys, they being used to control the operation of type bars writing the final letters. The keys marked O, A, U, I, E, which are to the front and below the space key are medial letter keys, they being used to control the operation of type bars writing the medial letters.
- The initial letters which consist chiefly of consonants are ordinarily used at the beginning of words or syllables, the medial letters which consist entirely of vowels are ordinarily used medially in words or syllables, and the final letters which consist chiefly of consonants are ordinarily used at the end of words or syllables.
- It will be observed that all the letters of the alphabet do not appear on the keyboard, there being only eight initial letters shown, whereas there are twenty-one initial consonants and one vowel, making a total of twenty-two letters to be written on the eight initial letter keys. There are only ten final letters shown, whereas there are nineteen final consonants and one vowel in addition to fifteen suffixes and special consonant combinations which have been provided to facilitate the writing of certain words, making a total of thirty-four letters, suffixes, and special consonant combinations that must be written on the final letter keys. It has also been found necessary in order to facilitate the writing of certain words to provide nine special vowel combinations in addition to the five vowels shown on the medial letter keys, making a total of fourteen vowels and special vowel combinations to be written on the five medial letter keys. These letters and letter combinations which do not appear on the keyboard are written by means of combination of keys instead of single keys as in the case of the letters shown on the keyboard, the machine being so constructed that the simultaneous operation of certain keys, instead of writing the several letters represented by the single keys, will write another letter or combination of letters.
- To better explain this feature of the invention,

there is provided below a table showing the character to be written and the finger key or combination of keys used in writing the character, the left column headed "Characters" giving the character or letter to be written and the right column headed "Keys" giving the finger key or keys used in the writing of the corresponding letter or character.

The initial letter keys are adapted to be operated with the fingers of the left hand, the final letter keys with the fingers of the right hand, and the medial letter keys with the thumbs. By 35 using this method of fingering, it is possible for the operator to set up in the machine an entire word or syllable at one operation.

Should it be desired to write the word LIGHT the keys NR (which write the initial L as shown 40 in the above table of letters) are depressed by the fingers of the left hand, the medial key I by the right thumb, and the keys BNGT (which combination writes the final letters GHT as shown in the above table of letters) by the fingers 45 of the right hand. These keys are all depressed simultaneously and upon the release of the keys, the machine is set in operation, writing the letters L I G H T in the proper order, which order is accomplished through the action of a timing 50 means which releases the type bar actuating means for the types selected in a consecutive order from left to right, the type bars being arranged according to the order of their occurrence in the word.

55 Below is given the order in which type bars are arranged in the type basket, they being adapted to be actuated from left to right as herein-after set forth. The lower line of characters represents the lower case letters, or the characters written by the machine when the platen is shifted to lower position. The upper line of characters represents the capital or upper case letters, or the characters written by the machine when the platen is shifted to upper position. 60 Each type bar has two letters or characters formed thereon, the small and the corresponding capital as shown below.

Type bars for the first thirty-six letters are carried in the left or fixed type basket segment. The remaining thirty-five letters are carried in the right or movable segment of type basket. This is done to provide for the throwing of two type bars simultaneously, one in each segment of type basket as hereinafter set forth.

85 Mounted in the frame A is a cross bar 1 (Figure 1) which supports a shaft 2 on which is mounted a plurality of key levers 3 provided with finger keys 4. The forward ends of key levers are guided in comb guide 5. The rearward ends of key levers extend rearwardly beyond cross bar 1 and are engaged by springs 6 which serve to retain key levers in normal position. Intermediate the cross bar 1, and the comb guide 5 is a cross bar 7 which supports 90 a plurality of bell cranks 9. Each of said bell cranks is pivoted at 8 and provided on its rearwardly extending arm with pin 10 and on its upwardly extending arm with pin 11, said pins being adapted to engage slots 10a and 11a respectively.

95 Mounted above key levers are a plurality of selector bars indicated generally by the numeral 12, varying slightly in design as required to perform the type selecting function and indicated 130 specifically by the numeral 12 in combination with a letter. Said selector bars are slidably mounted at their forward and rearward ends in guides 25 and 26 respectively. Lying between selector bars and parallel thereto are auxiliary 110 selector bars indicated generally by the numeral 19 and specifically by the numeral in combination with a letter. Said auxiliary selector bars are provided according to the requirements of type selections and are mounted at their forward 115 and rearward ends in the same manner as selector bars.

115 Selector bars and auxiliary selector bars are provided with notches and projections on the edges thereof of the types 13, 14, 15, 16, and 28, 120 said notches and projections being provided to perform certain functions according to the requirements of type selections and being specifically referred to by their respective numeral in combination with a letter.

125 Pivotedly carried on each of said auxiliary selector bars 19 is a dog of the type 18 or 20, said dogs being provided to perform certain functions according to the requirements of type selections and specifically referred to by their respective number in combination with a letter. Dog 18 is provided on its forward end with transverse head 22 adapted to make contact with selector bars 12, said dog being normally held out of contact with selector bars by means of 130 spring 27. On the rearward end of dog 18 is provided shoulder 23 adapted to be acted upon by spring arm 17 which is carried on selector bars 12 for the purpose of rendering dog active by placing spring tension on the rearward end of said dog and raising the forward end into contact with selector bars. Dogs of the type 20 are provided on their forward ends with transverse heads 22 and are adapted to make contact with a plurality of selector bars or auxiliary selector bars and are held in contact position by spring 21.

135 Mounted at the rear of frame A and above selector bars is a cross bar 29 which supports shaft 30 on which is mounted a plurality of 140

145 selector bars 12 which are mounted on frame A and above selector bars 12.

levers 31. On the lower end of each of said levers is pivotally mounted a selector arm generally indicated by the numeral 33 and specifically indicated by the numeral 33 in combination with a letter. Selector arm 33 is provided on its forward end with contact head 32 adapted to make contact with selector bars 12 and auxiliary selector bars 19. Carried on cross bar 29 is a plurality of springs 33' adapted to make contact with selector arms for the purpose of retaining selector arms in contact with selector bars. There is also provided springs 37, one for each selector arm, for the purpose of retaining selector arm in forward or normal position.

15 On the upper end of lever 31 is pivotally mounted selector push bar 34 which is held in comb guide 35 by spring 36 and is adapted to act upon registering members of release rotor for the purpose of registering type selections in the manner herein-20 after explained.

As hereinbefore set forth, the five vowel keys are designed to control the operation of eight type bars giving a total of 14 vowels and special vowel combinations. The means by which this is accomplished is here set forth. For the sake of clearness and brevity the specification covers only a portion of the selections possible on the medial letter keys, the principles set forth being extended to the entire keyboard.

25 30 When finger key 4 is depressed, key lever 3 is carried downward, imparting a downward motion to rearwardly extending arm of bell crank 9 by means of slot 10a acting upon pin 10, tipping bell crank rearwardly. Pin 11 acting in slot 11a moves selector bar 12 rearwardly in its mountings 25 and 26. The dotted lines in Figure 6 shows fully depressed finger key and the resultant positions of related parts. The first part of rearward movement of selector bar moves 35 40 notch 13 under contact head 32 of selector arm 33, allowing contact head to drop down into notch as shown by dotted lines in Figure 6. This establishes contact between selector arm 33 and selector bar 12 so that further movement 45 of selector bar will move selector arm rearwardly, operating lever 31 and through push bar 34 registering the type selection in the manner hereinafter set forth. The operation for all single key letters is substantially the same as 50 above set forth.

Letters or combinations of letters which do not appear on the keyboard are obtained in the following manner. Should it be desired to write the vowel combination "IU", which does not appear on the keyboard and which is written by the combination of keys U, I, and E as hereinbefore set forth, the finger keys for U, I, and E are depressed simultaneously. This action through means previously explained moves selector bars 12u, 12i, and 12e rearwardly. The first part of this movement brings notches 28i and 28e of selector bars 12i and 12e into alignment with transverse head 22 of dog 18i and at the same time brings contact head 24 of spring bar 17a carried on selector bar 12a into contact with cam shoulder 23 of dog 18i, rendering dog active by means of spring tension exerted by spring bar 17a on shoulder 23 of dog, raising transverse head 22 of dog 18i into notches 28i and 28e. This movement also brings notches 28o and 28a of selector bars 12o and 12a into alignment with transverse head 22 of dog 18e and at the same time brings contact head 24 of spring bar 17e carried on selector bar 12e into contact with cam shoulder 23 of dog 18e, rendering dog active by means of spring tension exerted by bar 17e on shoulder 23 of dog, raising transverse head 22 of dog 18e into notches 28o and 28a. Further movement of selector bars will carry dogs 18e and 18i rearwardly, 55 60 moving auxiliary selector bars 19e and 19i. The second part of key movement brings notch 13i under head 32 of selector arm 33i and notch 13e under head 32 of selector arm 33e, but selector arms are prevented from dropping into notches 13i and 13e by reason of notches 14e and 14i provided in auxiliary selector bar 19i moving from beneath head 32 of selector arms 33i and 33e and allowing selector arm heads to rest on auxiliary selector bar, rendering selector arms inactive and preventing the letters I and E from registering. This movement also carries notch 13o under head 32 of selector bar 33o, but selector arm 33o is prevented from dropping into notch by reason of notch 14z being moved from under head of selector arm 33o and allowing selector arm to rest on auxiliary selector bar 19e, rendering said selector arm inactive and preventing the letter O from registering. Notch 13z is moved under head 32 of selector arm 33z, allowing selector arm to drop into notch 13z and rendering selector arm active. Notch 13x is also moved under transverse head 32 of selector arm 33x, but selector arm is prevented from dropping into notch 13x by reason of notch 14x provided in auxiliary selector bar 19e 65 70 75 80 85 90 95 100 105 110 115 120 125 130 135 140 145 150

arm active. This also brings notch 13i under head 32 of selector arm 33i and notch 13e under head 32 of selector arm 33e, but selector arms 33i and 33e are prevented from dropping into notches 13i and 13e by reason of notches 14i and 14e provided in auxiliary selector bar 19i moving from beneath heads 32 of selector arms 33i and 33e and allowing selector arm heads to rest on auxiliary selector bar, rendering said selector arms inactive and preventing the letters I and E from registering. This also moves notch 13x under transverse head 32 of selector arm 33x, allowing selector arm to drop into notch 13x rendering selector arm active. It will be observed that these functions serve to establish contact between selector arms 33u and 33x and selector bars.

Further movement of finger keys carries selector arms rearwardly by means of contacts above explained. The rearward movement of selector arms operates levers 31 and through push bars 34 registers type selections for the letters I and U in the manner hereinafter explained.

Should it be desired to write the vowel combination "EA" which does not appear on the keyboard and which is written by the combined action of keys O, A, I, and E, the finger keys are depressed simultaneously. This action through means hereinbefore explained moves selector bars 12o, 12a, 12i, and 12e rearwardly. The first part of this movement brings notches 28i and 28e of selector bars 12i and 12e into alignment with transverse head 22 of dog 18i and at the same time brings contact head 24 of spring bar 17a carried on selector bar 12a into contact with cam shoulder 23 of dog 18i, rendering dog active by means of spring tension exerted by spring bar 17a on shoulder 23 of dog, raising transverse head 22 of dog 18i into notches 28i and 28e. This movement also brings notches 28o and 28a of selector bars 12o and 12a into alignment with transverse head 22 of dog 18e and at the same time brings contact head 24 of spring bar 17e carried on selector bar 12e into contact with cam shoulder 23 of dog 18e, rendering dog active by means of spring tension exerted by bar 17e on shoulder 23 of dog, raising transverse head 22 of dog 18e into notches 28o and 28a. Further movement of selector bars will carry dogs 18e and 18i rearwardly, 110 115 120 125 130 135 140 145 150 moving auxiliary selector bars 19e and 19i. The second part of key movement brings notch 13i under head 32 of selector arm 33i and notch 13e under head 32 of selector arm 33e, but selector arms are prevented from dropping into notches 13i and 13e by reason of notches 14e and 14i provided in auxiliary selector bar 19i moving from beneath head 32 of selector arms 33i and 33e and allowing selector arm heads to rest on auxiliary selector bar, rendering selector arms inactive and preventing the letters I and E from registering. This movement also carries notch 13o under head 32 of selector bar 33o, but selector arm 33o is prevented from dropping into notch by reason of notch 14z being moved from under head of selector arm 33o and allowing selector arm to rest on auxiliary selector bar 19e, rendering said selector arm inactive and preventing the letter O from registering. Notch 13z is moved under head 32 of selector arm 33z, allowing selector arm to drop into notch 13z and rendering selector arm active. Notch 13x is also moved under transverse head 32 of selector arm 33x, but selector arm is prevented from dropping into notch 13x by reason of notch 14x provided in auxiliary selector bar 19e 150

moving from beneath head of selector arm and allowing selector arm to rest on auxiliary selector bar 19*e*, rendering selector arm inactive and preventing the letter I from registering. Projection 16*e* is moved under head 32 of selector arm 33*a*, raising lug 32*x* carried on transverse head of selector arm 33*a* into notch 14*y* provided in auxiliary selector bar 19*i*, so that further movement of auxiliary selector bar will carry selector arm rearwardly, rendering said selector arm active. The purpose of these functions is to establish contact between selector bars and selector arms 33*x* and 33*a* for the purpose of registering type selections for the letters E and A.

15 In writing the combination "EU" the keys O, A, U, and I are depressed simultaneously. The first part of key movement establishes contacts between selector bars and auxiliary selector bars 19*e*, 19*o*, and 19*i* in the manner hereinbefore explained. Notches 13*j*, 13*g*, and 13*h* are moved into alignment with transverse head 22 of dog 20, making contact between selector bars and auxiliary selector bar 19*u*. Further movement of keys moves notch 13*o* beneath selector arm 33*o* and notch 14*z* from beneath said selector arm, rendering said selector arm inactive and preventing the letter O from registering. Notch 13*z* is moved beneath selector arm 33*z* allowing it to drop into notch, rendering said selector arm active. Projection 16*e* is moved beneath selector arm 33*a*, preventing contact with notch 13*a* and rendering selector arm 33*a* inactive, preventing the letter A from registering. Projection 15 on auxiliary selector bar 19*u* makes contact with selector arm 33*u*, rendering said selector arm active. Notches 14*u* and 14*i* are moved from beneath selector arm 33*i*, preventing it from contacting with notch 13*i* and rendering selector arm 33*i* inactive, preventing the letter I from registering. These functions have served to establish contact between selector bars and selector arms 33*x* and 33*u* so that further movement of finger keys will serve to register type selectors for the letters E and U.

The above specification of type selecting mechanism covers only a portion of the medial letters, but the principles set forth are extended to the entire keyboard.

Extending transversely of machine in close proximity to rearward side of timer plungers 39 is a release rotor 38 adapted to be acted upon by selector push bars 34 and in turn to act upon timer plungers 39 for the purpose of tripping said plungers against timer balls 40. Said rotor is comprised of a plurality of cylindrical sections (Figure 14) corresponding in number to selector push bars 34, there being one for each type bar. Passing through said sections at right angles to the axis of said rotor is a slot 42 adapted to receive a slidable type registering member 43 adapted to be acted upon by selector push bars 34 for the purpose of registering type selections for letters or letter combinations set up on finger keys, said finger keys acting through the medium of selector mechanism as hereinbefore explained. Intermediate the ends of said slot an enlarged portion 42*a* is provided to receive a spring detent 44 having projection 44*a* which cooperates with notches 43*a* in slidable type registering member 43 for the purpose of retaining said type registering member in maximum forward or rearward position. The type registering member 43 is greater in length than the diameter of cylindrical section 41 and is designed to cooperate with spring detent 44*a* in such way that it is at all times projected either forwardly or rearwardly

beyond the periphery of said cylindrical section so as to form a lug thereon, said member being normally projected rearwardly.

In operation selector push bar 34 contacts rearwardly projecting end of slidable type registering member 43 and forces it into forward position, in which position it is retained by spring detent 44. The forwardly projected end of type registering member 43 forms a lug adapted to act upon knee 45 of timer plunger 39 for the purpose of tripping it against timer balls 40 when release rotor 38 performs half revolution, said release rotor being rotated one-half revolution for each operation.

Immediately above release rotor 38 and parallel thereto is a stationary member 46 presenting a concave surface toward said rotor, the forward edge of said member being closer to the periphery of rotor than the rearward edge. When said release rotor is rotated, the rearwardly projecting ends of slidable type registering members 43 are brought into contact with concave surface of stationary member 46 (Figure 16) and forced downwardly, projecting said type registering members on the opposite side of release rotor (Figure 17) so that when rotor has completed its one-half revolution all of said type registering members are projected rearwardly to again be acted upon by selector push bars 34. The ends of said stationary member 46 are secured firmly to side frame and provided with bearings 47 (Figure 3) in which end sections 48 of release rotor are journaled. Stationary member 46 also serves as a supporting bracket 49 (Figures 1 and 8) for the intermediate gear 50 of drive gear train.

The drive gear train is comprised of a driven gear 51 carried near the central portion of release rotor 38 and forming an integral part thereof, an intermediate gear 50, and a driving gear 52 carried on the driven member 53 of a one-round clutch. By the action of the one-round clutch and through the medium of a two to one gear ratio the required half revolution of release rotor is effected.

The one round clutch is carried on the electric 120 motor drive shaft 54 and is comprised of a loosely fitting driven member 53 and a driving member 55 keyed to motor drive shaft. Said driving member is provided with a recess 56 (Figure 9) in the face thereof adapted to engage contact head 57*a* 125 of a spring actuated clutch dog 57 which is carried in a recess 58 cut in driven clutch member 53. Clutch dog 57 has the form of a gib headed key with a gib on each end. Between the inner face of contact head 57*a* and the end of operating 130 slot 58 is interposed a spring 59 which constantly tends to move dog into engagement with driving clutch member 55. There is provided a clutch throw-out lever 60 (Figure 10) adapted to engage contact head 57*b* of clutch dog 57 and hold it 135 against movement. Clutch throw-out lever 60 is pivotally mounted on bracket 66 (Figure 3) carried on rear frame and is provided with a wedge shaped cam face 60*a* of arcuate form adapted to engage contact head 57*b* of clutch dog 140 57 and cam it out of engagement with driving clutch member 55. At the thick end of said cam face is provided a stop lug 60*b* extending beyond said cam face in such manner as to come in the path of the actuating head 57*b* of clutch dog 57 145 and arrest the movement of driven clutch member when it is disengaged from driving member. There is provided on the clutch throw-out lever 60 an arcuate flange 60*c* which presents an ear adapted to be engaged by hook 61*a* on trip off 150

pawl 61 carried on the rearward extension of universal bar 62. There is provided in flange portion 60c of clutch throw-out lever 60 a downwardly extending spring guide 63 adapted to be received at its lower extremity by a forwardly extending arm 61b of trip off pawl 61. Carried on spring guide intermediate the flange portion of clutch throw-out lever and the forwardly extending arm of trip off pawl is a compression spring 64 adapted to retain throw-out lever 60 in contact position. There is also provided on trip off pawl 61 an upwardly extending portion 61c adapted to come in the path of actuating head 57b of clutch dog 57 in such way that when driven 10 clutch member is revolved the side of actuating head 57b of clutch dog will strike said upwardly extending portion and move trip off pawl 61 rearwardly, disengaging hook 61a from ear 60c on clutch throw-out lever and allowing clutch throw-out lever 60 to be returned to normal position by the action of spring 64.

The universal bar 62 on which trip-off pawl 61 is carried is pivotally mounted near its center to side frame and is adapted to make contact at 15 its forward extremity 62a with key bars 3 in such way that the movement of key bars will carry forward end of universal bar downward. This action turns universal bar on its pivot, raising trip-off pawl 61 into contact position allowing 20 hook 61a to engage ear 60c of clutch throw-out lever 60. When finger keys are released, universal bar is returned to normal position by reason of spring 65 provided at its rearward extremity. This action moves trip-off pawl 61 downward, 25 which, being engaged with clutch throw-out lever 60, moves it out of engagement with actuating head 57b of clutch dog 57, allowing it to make 30 contact with driving clutch member 55. The rotation of driven clutch member 53 carries actuating head 57b of clutch dog against the upwardly extending portion 61c of trip off pawl 61, disengaging hook 61a from ear 60c of clutch throw-out lever 60, allowing it to be returned to contact position by spring 64. Further rotation of 35 driven clutch member brings actuating head 57b of clutch dog into contact with cam face 60a of clutch throw-out lever, camming clutch dog 57 out of engagement with driving clutch member 55, at which time actuating head 57b of clutch dog 40 comes into contact with lug 60b of clutch throw-out lever arresting the movement of driven clutch member. This action has effected one-half revolution 45 of release rotor 38, tripping all selected timer plungers 39 down against timer balls 40 and also resetting letter registering members 43 as hereinbefore explained.

There is provided a timing mechanism adapted to receive the type selections registered on the release rotor 38 and in turn to distribute said selections consecutively to type actions through actuating cams 71 of corresponding type bars. Said timing mechanism is comprised of a series of vertical plungers 39 arranged in parallel array extending transversely of machine (Figure 12) 50 and carried in two independent units conforming to the two type basket units, the left unit spanning the left half of the machine and controlling the type bars carried in the left type basket segment and the right unit spanning the right 55 half of the machine and controlling the type bars carried in the right segment of type basket. The two units of timing mechanism are synchronized so as to operate in harmony one with the other in such way that two type bars may be thrown 60 simultaneously, one in the left type basket seg-

ment and one in the right type basket segment. Timer plungers 39 are slidably mounted at their upper and lower ends in guides 65 and 66 respectively which are secured to side frames. Provided in the lower guide bracket 66 is a ball race 67 in which is carried a double row of interlocking balls 40 adapted to coat with the timer plungers 39 as hereinafter explained. Should it be desired rollers may be used instead of balls the rollers being adapted to be acted upon by the timer plungers in exactly the same manner as the balls; however, balls are preferable.

A construction employing the rollers instead of the balls is not disclosed in the drawings for the reason that the general construction is the same 90 in both constructions and both employ the same principle of operation.

On the lower end of each timer plunger 39 is provided a straight finger 39a (Figure 13) adapted to pass between timer balls (Figures 8 and 11) 95 and an offset finger 39b adapted to rest on timer balls as shown in Figure 11. To the forward portion of timer plunger is pivotally mounted a connecting link 68 which connects plunger to actuating cam release lever 69. Actuating cam release 100 lever 69 is pivotally mounted on actuating cam bracket 70 and has a forwardly extending arm 69a on which is carried a roller 69b adapted to run in roller race 71e provided in face actuating cam 71.

Actuating cam 71 (Figure 15) is provided with 105 a rock block 71a loosely carried on an extending hub 71b of actuating cam. A compression spring 71c is interposed between a radially extending projecting portion of rock block 71a and a corresponding support 71d in the face of actuating 110 cam. The opposite end of rock block extends outwardly and forms the side of a radial portion of roller race 71e. When in neutral position, a flat 71f on the periphery of actuating cam is presented toward power roller 72, breaking contact 115 between power roller and actuating cam.

When timer plunger 39 is tripped and offset finger 39b rests on balls 40, the cam release lever 69 is in the position shown in Figure 16 and rock block 71a is about to escape from release roller 120 69b. The action of spring lever 73 against cam forces the upper corner of rock block 71a against the lower portion of release roller 69b which tends to turn release lever 69 on its pivot, thus forcing timer plunger 39 down against timer ball 40. 125 When timer ball 40 is allowed to move from beneath offset finger 39b, timer plunger 39 moves downward into extreme actuated position, (Figure 17) and rock block 71a is allowed to escape from release roller. There is provided on cam bracket 130 70 a spring lever 73 with torsion spring 74 which constantly forces lever against pin 71g projecting from side of actuating cam. This action constantly tends to move actuating cam into contact with power roller 72 so that when rock block escapes 135 from release roller, cam is moved into contact position. When cam 71 has completed one revolution and effected a corresponding type action, the flat face 71f is presented toward power roller 72 and the rock block 71a makes contact with roller 69b carried on release lever 69, arresting the movement of cam. The spring 71c provided on the opposite end of rock block serves to cushion the contact of roller 69b with rock block 71a. The movement of release lever 69 effected by roller race 71e in face of actuating cam 71 acting upon roller 69b has served to return timer plunger 39 to normal position.

Provided at the extreme left end of both the left and right ball races 67 is a wedge shaped timer- 150

ball reset plunger 75 (Figures 3 and 8) which passes between the balls and the left end of ball race. When ball reset plungers 75 are moved downward, the enlarged portions of said plungers force timer balls 40 to the right so that openings between balls are in the proper position to receive straight fingers 39a provided on timer plungers 39. The release rotor 38 is provided with suitable lugs 38a (Figure 3) to engage the rearwardly extending ends of ball reset plunger arms 76 for the purpose of forcing said reset plungers downward and resetting balls in the manner above explained.

Assuming that selections have been registered on release rotor 38 calling for a multiplicity of type actions, when finger keys 4 are released, release rotor 38 is caused to turn one half revolution, which is accomplished by means of the gear train and one-round clutch hereinbefore explained. This action carries timer ball reset plungers 75 downward, resetting timer balls 40. At the same time release rotor trips selected timer plungers 39 down against timer balls 40, the straight finger 39a passing into spaces between balls and the offset finger 39b resting on the top and to the right of center of timer balls (Figure 11). It will be observed that so long as ball reset plungers 75 remain in a downward position, timer plungers 39 are prevented from moving into extreme actuated position and thereby releasing actuating cam by reason of timer balls 40 being retained under offset fingers 39b of timer plungers. When ball reset plungers are returned to normal position, which is effected by spring 77, the ball under the offset finger of the first timer plunger from the left is allowed to move to the left sufficiently to allow plunger to move downward into extreme actuated position and release actuating cam 71 as hereinbefore explained. The straight finger of said timer plunger serves to retain all balls to the right thereof in a reset position, thus preventing any other tripped timer plungers from moving downward and releasing other actuating cams while the first cam is in operation. When actuating cam has completed one revolution and effected a corresponding type action, timer plunger is returned to normal position as previously explained. The resulting withdrawal of straight finger 39a of timer plunger from balls allows the ball under the offset finger 39b of the next tripped timer plunger to the right to move to the left sufficiently to allow plunger to move downward into extreme actuated position, releasing the corresponding actuating cam, and so on until all type selections have been printed. The above described action may take place simultaneously in both right and left timer units, making it possible for two type bars, one in the left and one in the right type basket segment to be actuated at the same time.

Extending transversely of frame and located between type bar actuating cams and timer plungers is the power roller 72 supported in bearings 73 carried on side frame of machine. The power drive of said roller is effected through the medium of a V belt 79 connecting drive pulley 80 carried on motor drive shaft 54 with a corresponding pulley 81 carried on power roller. In operation power roller is adapted to run continuously and transmit driving power to actuating cams through friction contact.

The type bar actuating mechanism is comprised of a type bar actuating cam as hereinbefore described, the connecting linkage, and the type bar assembly. Extending transversely of frame and attached thereto is a bar 82 upon

which the supporting brackets 70 of the type bar actuating cams are mounted. Each bracket carries a type bar actuating cam 71 with its respective spring lever 73 and release lever 69. Said actuating cams are arranged in two banks mounted one above and one below the supporting bar 82, said bar is mounted just forward of power roller 72 and serves to hold the cams in correct relation thereto.

There is provided on each of said actuating cams a crank pin 71h (Figure 15) on which is mounted a connecting arm 83 which serves to connect crank pin with swingable link 84 depending from a bracket 85 carried on the forward portion of frame. To a forwardly extending arm 84a of said swingable link is attached a type bar actuating link 86 which extends upward and is attached at its upward end to type action, and serves to transmit operating motion thereto.

The type action is comprised of a reciprocating type bar 87 (Figure 17) having upper and lower case types formed on the usual type head 88 carried on the rearward end of type bar. Besides the type head, other essential parts of type action are a bell crank 89 pivotally mounted on hanger 90 and connected to upper end of actuating bar 86, a type bar carrier arm 91 pivotally connected at its lower end to type action hanger 90 by means of a sublink 92, the upper end being connected to the forward end of type bar 87, a weighted toggle 93 connecting bell crank 89 to central portion of type bar carrier arm 91, and a type bar guide link 94 depending from type action hanger. The rearward side of type basket frame 110 is provided with comb guides 95 to receive the rearward end of type bars. Each of said type bars is provided with a slot 87a passing lengthwise thereof and adapted to receive pin 96 provided in comb guide for the purpose of supporting the rearward end of type bar against vertical movement. The aforementioned weighted toggle carries a weight 93a on the upper portion of forward link and is provided with a pin 93c and a slot 93b for the purpose of limiting the turning movement of toggle links about pivot. A spring 93b is provided for the purpose of retaining toggle in retracted position.

In operation the type bar actuating cam 71 is rotated by means of power roller 72, moving connecting arm 83 carried on crank pin 71h rearwardly, which pulls the forwardly extending arm 84a of swingable link 84 through actuating link 86. This action moves the downwardly extending arm of bell crank 89 rearwardly. The weighted toggle 93 being limited in its turning movement about toggle pivot by means of pin 93c and slot 93d serves as a push link between bell crank and type bar carrier 91. The rearward movement of downward extending arm of bell crank carries type bar carrier 91 rearwardly by reason of push link action of toggle 93. This action through connection of type bar carrier 91 to forward end of type bar 87 projects type bar rearwardly toward printing center, the depending guide link 94 coacting with type bar carrier 91 and sublink 92 in such way as to give an approximate straight line movement to the forward end of type bar, the rearward end being guided by pin 96 in slot 87a. When type bar actuating cam is in its extreme actuated position, the type bar and connecting linkage are in the position shown by dotted lines in Figure 1, being carried to this position by acti-

- ating cam. The momentum of the type bar supporting linkage together with the momentum of weight 93a on forward link of toggle 93 serves to straighten toggle joint and carry type bar into printing position as shown in Figure 17. The return of actuating cam to normal position retracts the type bar, spring 93b serving to retract toggle 93.
- There is provided a type basket located on the top of the forward portion of frame in front of the platen in such a way as to place writing centers in full view of operator. Said type basket consists of two segmental units, right and left, having separate but similar frames. Each of said frames is formed of a sheet metal band 97 (Figure 2), the front of which is of arcuate form, the sides extending rearwardly therefrom approximately along lines radiating from writing centers, and serving to connect said arcuate front to comb guide 95 which forms the rearward portion of said frame. The forward end of type action is secured to arcuate front of type basket frame by means of type action hanger 90, the rearward end of type action passing through comb guide 95 and being supported by pins 96.
- The left segment of type basket is secured at the front to the frame of machine and at the rear to a cross member 98 extending transversely of machine and secured to the side frame. Said left type basket segment being rigidly mounted to frame has a fixed writing center 99 (Figure 18) which is more definitely determined by a fixed type guide 100 secured to frame in close proximity to platen. The type bars carried in said left segment of type basket radiate from fixed writing center 99 in arcs struck in both vertical and horizontal planes, said type bars being arcuately arrayed in three tiers radiating from said fixed writing center.
- The right segment of type basket is movably mounted on a track 98a (Figure 2) running transversely of the frame and parallel with carriage track, said type basket track being formed on the cross member 98 to which rearward portion of fixed type basket segment is secured. To the lower side of right segment of type basket are attached lengths of track 103 provided with races corresponding to ball races in stationary track 98a. Interposed between said races are balls 104 which neatly fill the spaces and are held in place by suitable means. The aforesaid track forms the chief support for the movable segment of the type basket and allows a movement of the type basket parallel to the platen. There is secured to the front of movable type basket segment a short length of rod 105 which is slidably mounted in a bearing 106 forming a support and being attached to right front corner of typewriter frame. This rod serves as a support for the front of type basket and receives the component of the force imparted thereto by the power means operating the type bars of said segment. Between a collar 107 provided about the central portion of rod 105 and fixed support 106 is interposed a spring 107a. The extreme right end of the forward track 103 carried on said type basket segment terminates in a support 108 similar to the one provided for the front of said segment and is provided with a similar spring 109. Springs 107a and 109 tend constantly to move the type basket to the left against suitable stops and thus retain it in normal position.
- The right type basket segment being movably mounted as before explained has a movable writing center 101 (Figure 18) which is more defi-
- nitely determined by a movable type guide 102 carried on a rearwardly extending arm 102a attached to the rearward right corner of movable segment; said type guide is carried in close proximity to the platen and establishes the writing center in the same horizontal plane as the aforesaid fixed type guide of the left type basket segment. The type bars carried in the right segment of type basket radiate from writing center in the same manner as type bars carried in left type basket segment. The right type basket segment being movable transversely of the frame and parallel to the platen and carrying movable type guide, it is therefore obvious that as the right type basket segment is moved to the right, its respective writing center is also moved parallel along platen (see Figures 19 and 20).
- The divided type basket is provided for the purpose of allowing the simultaneous operation of two type bars. The type bars carried in the fixed segment write the initial letters of a word and the type bars carried in the movable segment write the final letters. To illustrate: Should it be desired to write the word CHURCH, selections for all types are made with one finger 100 operation as hereinbefore explained. The letters CHU are written with left type bars and the letters RCH with the right type bars. The right segment of type basket is automatically carried to the right three spaces, moving the writing center of type bars carried in said segment an equal number of spaces to the right. Upon the release of the finger keys both the right and left type bars begin operating at the same time. The letter C is written on the left and three 110 spaces to the right the letter R is written, thus: C—R—. The second type action writes the letters H and C, thus: CH—RC—. The third type action completes the word, thus: CHURCH. Thus the word is written in only half the time 115 required where only one type bar is thrown at a time. The advantages of such an arrangement are obvious.
- Located centrally between the two type basket segments and extending from the front of type- 120 writer frame to a point near the carriage rack is a shaft 110 carrying gears 111, 112, 113, and 114, all of which are fixed to a shaft. The front and rear ends of shaft 110 are journaled in bearings supported by frame. Attached to the front 125 and rear of lower left side of right movable type basket segment are two short racks 115 and 116 which extend transversely of the machine frame and lie parallel to the line of movement of movable type basket segment. The underside of said 130 racks are provided with teeth adapted to mesh with gears 111 and 112 of the aforesaid shaft assembly. Gear 113 of said assembly is adapted to be acted upon by a rack 117 (Figure 24) which is actuated by a specially designed type basket 135 spacing mechanism as hereinafter described. The action of rack 117 on gear 113 imparts a turning movement to shaft 110 which is transmitted to gears 111 and 112 carried on shaft 110. The action of these gears on type basket segment 140 racks 115 and 116 moves said type basket segment to the right.
- The type basket spacing mechanism is located on the left side of machine, being secured to typewriter frame on the left end and extending to the 145 right beyond the center of machine and secured to upper frame at the right end (Figure 2). Said mechanism consists of a plurality of wedge shaped plungers 118 (Figure 23) placed vertically and in parallel array. Said plungers are com-

prised of a head 118a of suitable thickness which tapers abruptly to a thin shank 118b (Figure 24), the difference in thickness of said plunger head and shank being equal to one letter space. 5 Interposed between plungers 118 are slideable spacing blocks 119 supported in a channel frame 120 which retains said slideable blocks against vertical and lateral movement, but allows movement in a line of travel parallel with the movement of movable type basket segment. Said supporting channel is securely mounted to the left side of frame at one end, the other end being secured to upper frame and provided with a slideable follow block 121 having a square end loosely fitting the interior of channel, the other end terminating in a round portion 121a upon which is carried a compression spring 122 and which is slidably mounted in a suitable bearing 123. One end of said spring bears against bearing, the other 10 bears against enlarged head of follow block, thus tending to force follow block to the left against the alternate series of spacing blocks 119 and wedge shaped spacing plungers 118. There is provided a type basket spacing rack 117 which is attached to the forward side of follow block 121 by means of a screw 124 passing through a slot 125 carried in type basket spacing rack 117. Carried on type basket spacing rack is a projection 171a (Figure 2) to which is attached a spring 126, the other end of which is attached to a similar projection 172 on spacing mechanism housing 120. Spring 126 serves to retain spacing rack 117 in normal position. Said spacing rack is of the same pitch as the aforesaid racks attached to type basket segment and carries on its upper side a plurality of notches of buttress form and of the same pitch as the aforesaid rack teeth, each of said teeth being equal to one letter space. The right end of said rack is supported in suitable bearing 129 carried on type basket supporting member 98, the left end of said rack being supported by screw 124 passing through slot 125 and slideably securing said rack to follow block 121. Above said rack and supported on frame is a dog 127 adapted to engage buttress notches provided in the upper side of type basket spacing rack 117 when said rack is moved to the right as is the case when type basket spacing plungers 118 are forced between spacing blocks 119.

Attached to shank 118b of type basket spacing plungers is a connecting link 128 which is fastened on its lower end to an auxiliary plunger 130 (Figure 13) coacting with timer plungers 39 of left timer unit for the purpose of actuating said type basket spacing plungers, there being an auxiliary plunger for each timer plunger contained in left timer unit. Each of said auxiliary plungers is adapted to be carried in upper and lower guides 65 and 66 and in the same manner as timer plungers, and is provided with a forwardly extending portion 130a to which is attached type basket spacing plunger connecting link 128. On the lower rearward portion of auxiliary plunger 130 is provided a projecting lug 130b adapted to make contact with knee 45 of left timer plunger 39 for the purpose of tripping the coacting timer plunger, the release rotor 38 acting upon the lug 130b of auxiliary plunger instead of directly upon the knee 45 of timer plunger 39 as is the case with timer plungers working in right timer unit.

When type selections are made which involve the operation of type bars carried in the left seg-

ment of type basket, the release rotor 38 is revolved, thereby tripping the timer plungers 39 and auxiliary plungers 130 in the manner hereinbefore explained. Each auxiliary plunger tripped carries its corresponding type basket spacing plunger 118 down between spacing blocks 119, causing the spacing mechanism to be lengthened a number of spaces equal to the number of spacing plungers forced downward between spacing blocks minus one. To illustrate: If a four letter combination be set up which involves the operation of type bars carried in the left segment of type basket, the type basket spacing mechanism is lengthened three letter spaces to the right, the width of one space being required to take the lost motion out of the mechanism, said letter space amounting to the displacement of one type basket spacing plunger, the remaining three aforesaid plungers serving to lengthen the spacing mechanism. As they are forced downward between spacing blocks, the movable end of spacing mechanism carries follow block 121 to the right, which in turn moves type basket spacing rack 117 to the right through the action of screw 124 bearing against end of slot 125 provided in spacing rack 117. The dog 127 drops behind each notch as it passes beneath said dog in a right hand movement and prevents the return of spacing rack when the spacing plungers are forced upward to normal position by the return of timer and auxiliary plungers to rest position. However, the follow block 121 by reason of the spring pressure exerted on it by spring 122 is returned to normal position as spacing plungers are forced upward to normal position, it being free to move to normal position by reason of loosely fitting screw 124 sliding in slot 125 provided in type basket spacing rack 117. On the outer end of rounded portion 121a of follow block which projects beyond bearing support 123 is carried a camming member 131 which upon its return to normal position passes under inclined projection of dog 127 and tends to raise dog out of engagement with notches on type basket spacing rack 117. As dog escapes from notch of type basket spacing rack, said rack is returned to normal position by action of spring 126, the movable type basket segment being returned to normal position at the same time by the action of springs 107a and 109.

There is provided a platen positioning mechanism for the purpose of setting platen in proper writing position to fixed type basket writing center after selections have been written requiring the operation of type bars carried in movable type basket segments as follows: On the end of type basket spacing rack locking dog 127 which extends to the left beyond its fulcrum point 127c is provided a slot 127a designed to engage a slender projection 132a (Figures 25 and 28) of a bell crank 132 pivoted on a support 133 carried by main supporting bracket 129 of type basket spacing mechanism. The lower end of said bell crank carries a pin 132b projecting from the side and engaging an L shaped slot 134a provided in forward end of escapement rack yoke 134. The escapement rack 135 is carried on the platen carriage, being swingably mounted and normally held in mesh with gear wheel 137 of escapement mechanism by two opposing springs 136 (Figure 21) one located on each side of said rack. Extending at right angles to and below escapement rack is provided yoke 134, having projections 134b and 134c extending upwardly on either side of escapement rack 135. Yoke 134 serves to move

- rack 135 from off gear 137 carried on escapement wheel shaft and on to the fourth and end most gear 114 of type basket spacing shaft assembly. The aforementioned yoke is swingably mounted 5 by means of links 138 and 139 depending from frame and attached at their lower ends to the ends of a swingable cross member 140. Cross member 140 has two projections extending upwardly, the forward projection 140a forming a 10 pivot for the yoke 134, said pivot being near the center of yoke. The rearward projection 140b of swingable cross member carries a loosely pivoted lever 141 of the first order, the forward end of which is pivoted to the rearward end of yoke 134. 15 The rearward end of said lever has attached thereto a spring 142 which extends forwardly and is mounted at the pivot of yoke 134. Said spring exerts sufficient force to normally restrain forward end of yoke in an up or down position as it 20 has been placed by mechanical means.
- For the purpose of placing yoke 134 in downward or contact position there is provided rock shaft 147 (Figure 3) placed immediately to the front of timer plungers and extending transversely of frame the entire length of right timer unit. Rock shaft 147 is provided with actuating ball 146 which is adapted to make contact with forwardly projecting lugs 39c carried on timer plungers 39 of the right timer unit. Said rock 25 shaft is also provided with a rearwardly extending arm 149 to which is attached the lower end of spring 145, the upper end being attached to the forward end of yoke 134. Provided on rock shaft is forwardly extending arm 150 provided on its 30 forward end with pin 150a adapted to work in slot 151a provided in yoke stop lever 151. The lower end of stop lever 151 is pivotally mounted on suitable bracket at 148 and is provided with spring 152 which serves to retain said stop lever in normal or forward position. The upper end of stop 35 lever is provided with stop pin 151b which is adapted to make contact with forward end of yoke 134 for the purpose of locking yoke against forward movement.
- 40 For the purpose of returning yoke 134 to normal position when it has been moved into contact position, there is provided a lever 143 (Figures 25 and 26) of the first order pivotally mounted on supporting member 129, spring 144 serving to retain lever in normal position. Provided on type basket spacing rack 117 is a downwardly extending arm 117b adapted to act upon beveled end of lever 143 for the purpose of forcing it downward into position shown in Figure 25. The opposite end of lever 143 makes contact with the forward end of yoke 134 and raises it into normal position as lever 143 is turned on its pivot by the action of arm 117b on beveled portion of said lever.
- 45 In operation, assuming that type selections have been made requiring the operation of a greater number of type bars in the right type basket segment than in the left, the corresponding timer plungers and auxiliary timer plungers are tripped 50 to retain lever in normal position. Provided on type basket spacing rack 117 is a downwardly extending arm 117b adapted to act upon beveled end of lever 143 for the purpose of forcing it downward into position shown in Figure 25. The opposite end of lever 143 makes contact with the forward end of yoke 134 and raises it into normal position as lever 143 is turned on its pivot by the action of arm 117b on beveled portion of said lever.
- 55 In operation, assuming that type selections have been made requiring the operation of a greater number of type bars in the right type basket segment than in the left, the corresponding timer plungers and auxiliary timer plungers are tripped 60 by the action of release rotor as hereinbefore explained. This action through means before described spaces movable type basket segment to the right the required number of spaces. As type basket spacing rack 117 is moved to the right, dog 65 127 is brought into engagement with notches on upper edge of rack by the action of spring 127b, locking rack against movement to the left. This retains movable type basket segment in spaced position. Projection 39c provided on right unit 70 timer plungers acts upon actuating ball 146 of rock shaft 147 and moves it into position shown by dotted lines in Figure 21. The action of pin 150a in slot 151a provided in stop lever 151 moves stop lever into rearward position, stop pin 151b coming into contact with forward end of yoke 134. This serves to lock yoke 134 against forward movement until all tripped timer plungers of right timer unit have been returned to normal position. When rock shaft 147 has been moved into actuated position, tension is placed on spring 145, which being attached to the forward end of yoke 134 tends to pull downwardly on said yoke. The action of spring 127b in bringing dog 127 into contact with type basket spacing rack 117 raises the end of dog carrying slot 127a, which acts upon slender projection 132a provided on bell crank 132, turning bell crank on its pivot 133. This action carries pin 132b rearwardly in slot 134a. When pin 132b is brought under the vertical portion of slot 134a, the forward end of yoke 134 is allowed to drop downward in response to spring 145. This raises the rearward end of yoke 134, which, acting upon lever 141, trips said lever into position shown in Figure 27, said lever and yoke being retained in tripped position by spring 142.
- When type actions have been completed in left segment of type basket, spacing plungers 118 are returned to normal position, allowing follow block 121 to be returned to normal position by the action of spring 122. The camming member 131 carried on rounded portion 121a of follow block is brought into contact with beveled end of dog 127. This action tends to raise dog out of engagement with type basket spacing rack 117. Dog 127 is prevented, however, from raising out of engagement with spacing rack 117 by the action of stop lever 151, which prevents yoke 134 from moving into forward position and through the medium of bell crank 132 which has contacted yoke 134 by means of pin 132b engaging the upper portion of L slot 134a in the manner shown in Figure 27 prevents any action of dog 127. When type selections in right type basket segment have been written, timer plungers 39 are returned to normal position allowing rock shaft 147 to assume its normal position. This returns stop lever 151 to normal position, releasing yoke 134 allowing it to move into forward position (Fig. 28) in response to action of camming member 131 on dog 127, this action being transmitted to yoke 134 by means of bell crank 132, pin 132b acting in vertical portion of slot 134a serving to establish the proper contact for moving said yoke.
- The moving of yoke 134 brings projections 134c into contact with rearward side of escapement rack 135, moving it out of mesh with escapement gear 137 and into mesh with gear 114 which is carried on type basket spacing shaft 135 110. With escapement rack 135 engaging type basket spacing shaft gear 114, it is obvious that as type basket is moved to left, platen carriage will be moved to the left an equal distance and vice versa. When movable segment of type basket has returned to normal position, the platen being carried with it is in the proper position to receive further type actions from either the left or right type bars. As type basket returns to normal position, projection 117b makes contact with trip lever 143 and returns it to normal position (Figure 25), which action raises the forward end of yoke 134, tripping yoke back to normal position and disengaging it from pin 140 11.

132b, allowing escapement rack 135 to return to normal position and into mesh with gear 137.

The letter spacing mechanism which is adapted to be operated by timer plungers 39 is comprised of an escapement wheel 153 mounted on a shaft 154, a gear wheel 137 affixed to the end thereof, and a rack 135 affixed to platen carriage and adapted to engage gear wheel 137. The escapement shaft 154 lies in exact alignment with the hereinbefore described type basket spacing shaft 110. The gear wheel 137 of the escapement shaft assembly is located immediately beneath the carriage rack 135 which is normally held in mesh therewith. Below said escapement wheel 15 and in close proximity thereto is a transverse rock shaft 155 (Figure 12) which spans the left timer plunger unit and is pivotally mounted to the frame at its extremities. Said rock shaft comprises a box like frame 156 at its right end in which are carried the usual escapement dogs of the conventional spacing mechanism. On the forward side of rock shaft assembly extending forwardly and horizontally thereto is affixed a ledge 155a adapted to be acted upon by projections 39d provided on the rear edge of timer plungers 39 of left timer unit. When plungers are actuated, said projections make contact with ledge 155a of rock shaft 155 and thereby rock escapement box 156 sufficiently to allow the escapement wheel to turn the space of one tooth, thus accomplishing the letter spacing of platen in the conventional manner. When the timer plunger is returned to an upward or normal position, the rock shaft is released and returned to normal position by spring 158, and is again set so as to perform the next letter spacing operation.

The right unit of said letter spacing mechanism is comprised of an elongated gear 157 extending transversely of typewriter frame and spanning the width of the right unit of timer plungers and is in close proximity thereto. Said elongated gear is journaled at its extremities in bearings supported on frame. Provided on the rearward edge of the right unit timer plungers 39 is a lug 39e adapted to act upon the teeth of said elongated gear. There is provided a subshaft assembly parallel to the elongated gear 157 of the right unit spacing mechanism and the rock shaft 155 of the left unit and overlapping the ends thereof. On subshaft 158 is carried a ratcheting gear 159 adapted to mesh with the elongated gear 157, said gear having ratchet teeth 160 provided in the face thereof adapted to mesh with like teeth provided in the face of gear 161 (Figure 2) which is fixedly mounted on subshaft 158. Spring 162 carried between collar 163 and ratcheting gear 159 serves to hold ratchet teeth of said gears in contact. On an arm 164 extending rearwardly from the outer end of follow block 121 of type basket spacing mechanism is provided escapement actuating pawl 165. Escapement actuating pawl 165 is comprised of a roller 166 normally held in contact with the teeth of fixed subgear 161, and a forwardly extending arm 165a normally located under the edge of a rearwardly extending ledge 156a (Figure 12) of the spacer box 156. When right timer plungers are tripped down, the projections 39e on rearward edge of timer plungers contact elongated gear 157 and turn it in an anti-clockwise direction, which turns the ratcheting gear 159 on the sub-shaft 158, said gear ratcheting against fixed sub-gear 161. As timer plungers are returned to normal position, the projections 39e on their rear-

ward edges contact elongated gear 157 and turn it in a clockwise direction. This turns the sub-ratcheting gear 159 which meshes with ratchet teeth on fixed subgear 161, imparting movement to said fixed gear. As fixed gear 161 is revolved the roller 166 on escapement actuating pawl 165 rides over the teeth of fixed gear, causing the forwardly extending arm 165a of escapement actuating pawl to strike the rearwardly extending ledge 156a of spacer box 156, tripping it forwardly and actuating the letter spacing mechanism as hereinbefore explained.

It will be observed that the left timer plungers actuate the letter spacing mechanism on a downward movement or at the beginning of a type action and the right timer plungers actuate the letter spacing mechanism on an upward movement or at the ending of a type action. This is done in order to provide for cases in which a two letter combination is set up, one letter in each segment of type basket. The two corresponding type bars being thrown simultaneously, the left type bar spaces on its printing stroke and the right type bar spaces on its return stroke, giving two letter spaces for the two letters printed. However, should a five letter combination be set up on the machine, two letters to print with left type bars and three with the right type bars, the right type basket segment will space over one space as hereinbefore explained. The escapement actuating pawl 165 carried on rearwardly extending arm 164 provided on type basket spacing mechanism is moved to the right from beneath rearwardly extending ledge 156a of spacer box 156, preventing the spacing action of right type bars. When the first type bars in each segment are thrown, they being thrown simultaneously, the left spacing mechanism imparts the spacing movement, one spacing function being sufficient. As type bar in left unit is actuated, the corresponding timer plunger 39 is returned to normal position. This action returns auxiliary plunger 130 to normal position by reason of lug 130b extending over knee 45 of timer plunger 39, which action forces corresponding type basket spacing plunger 118 from between spacer blocks 119, allowing follow block 121 to move to the left one space, which carries escapement actuating pawl 165 beneath ledge 156a of spacer box 156. When the next two type bars are thrown, the left one is spaced on the printing stroke and the right one on the return stroke, giving two letter spaces which are necessary in order to place the platen in the proper relation to the right type bar printing center 101. When the next letter is printed, the type basket is returned to normal position and platen reset as previously explained.

For the purpose of performing the spacing function when type bars are not thrown, there is provided an actuating cam 71 (Figures 3 and 12) which is adapted to be released in the same manner as other actuating cams except that releasing roller 69b is carried on arm 167a extending from space function rock shaft 167 which is provided at each end with rearwardly extending arms 168. These arms are connected to timer plungers 39 by means of connecting links 68. The arm carried on the left end of rock shaft is connected to timer plunger working in the extreme right end of left timer unit and the arm carried on the right end of rock shaft is connected to timer plunger working in the extreme right end of right timer unit. It is obvious that with such construction, it is impossible for the space function actuating cam to be released so long as

timer plungers are tripped in either left or right timer units. This is done in order that a space function may be set up on the keyboard at the same time type selections are made, the type selections being written before the space function is accomplished. The action of the type function actuating cam 71 is imparted to escapement mechanism by means of projection 39d acting upon ledge 155a of rock shaft 155, projection 39d being provided on the timer plunger working in the left timer unit. The timer plunger working in right timer unit does not actuate the spacing mechanism, but serves only to time the action of spacing function actuating cam.

15 For the purpose of more fully explaining this invention there is here provided a brief explanation of the operation of a typewriting machine embodying this invention.

Should it be desired to write the word 20 ASTROLOGY □ (the block □ represents a space function) the finger keys ASTR being initial letter keys are depressed with the fingers of the left hand; the fore finger, being placed so as to contact both the R key and the space key, serves to 25 operate both keys. The key O being medial is depressed with the left thumb, and the keys LGY, which write the suffix LOGY, being final letter keys are depressed with the fingers of the right hand. These keys are all operated simultaneously.

This action by means of type selecting mechanism registers the letters A S T R O L O G Y □ from left to right on the release rotor. When finger keys are released and return to normal position, 35 the one-round clutch is released and release rotor is turned one-half revolution, tripping the timer plungers for the corresponding letters, the left timer unit receiving ASTRO and the right unit receiving LOGY, both units coacting to receive 40 the single spacing function. The tripping of left timer plungers by means of type basket spacing mechanism spaces the right segment of type basket to the right four spaces to provide space for writing the letters of left unit. Upon the release of timer ball reset plungers, the first timer 45 plunger from the left in each timer unit is allowed to move down into maximum position, releasing the actuating cams for the corresponding type actions. When actuating cams have completed one revolution, they are arrested, the timer 50 plungers being returned to normal position. This action releases the next plungers in order, and so on until all selections have been written, the space function coming after all letter selections 55 have been written. The letter spacing for the entire word is accomplished by the left unit, the right unit spacing mechanism being rendered inactive by the action of right type basket spacing mechanism as hereinbefore explained.

60 The development of the word is as follows: When the first two type bars are thrown, one in each type basket segment, the word appears as follows: A---L---; after the second type action AS---LO---; after the third type action AST---LOG---; after the fourth type action ASTR---LOGY---; after the fifth type action ASTROLOGY---; and after the sixth action ASTROLOGY □, the complete word with a space 65 function following it, the sixth action serving to impart the spacing function. When the word is completed, the movable segment of type basket is returned to normal position and the platen is positioned for receiving further actions from type 70 bars.

Variations of construction and arrangement of parts may be resorted to without departing from our invention, and portions of the improvements may be used without others.

Having thus described our invention, we 80 claim:

1. In a typewriting machine having types and a platen, key controlled means for selecting types to be actuated comprised of a plurality of bars movable by finger keys and provided with notches and projections on the edges thereof according to the requirements of type selections, contacted by transverse members in such manner that the movement of said bars will line the notches and projections provided thereon up with the transverse members in such way as to cause said members to move into said notches and thereby establish contact for registering type selections; said type selecting mechanism being so designed that the movement of either a single bar or a combination of bars will establish contact for registering a predetermined type selection or combination of selections; and the combination therewith of means for registering type selections, means for actuating type bars, means 100 for imparting type selections to actuating means, timing means for consecutively releasing actuating means, and a keyboard comprised of finger keys adapted to control the operation of type selecting means. 105

2. In a typewriting machine having types and a platen, key controlled means for selecting types to be actuated comprised of a plurality of movable bars, certain of said bars being directly movable by finger keys, other of said bars being provided with dogs pivotally mounted thereon and adapted to make contact with notches provided in the edges of said bars directly movable by finger keys for the purpose of rendering said other bars operable, said bars being provided with notches and projections according to the requirements of type selections, a plurality of arms provided with transverse heads adapted to make contact with said bars in such manner that the movement of said bars will line said notches up with the transverse members, allowing said members to move into the said notches and thereby establishing contact for registering type selections, substantially as set forth; and the combination therewith of means for registering type selections, means for actuating type bars, means for imparting type selections to actuating means, timing means for consecutively releasing actuating means, and a keyboard comprised of finger keys adapted to control the operation of type selecting means. 110

3. In a typewriting machine having key controlled means for selecting types to be operated, the combination of means for registering type selections comprised of a plurality of slidable members carried in a revoluble member and projecting from the periphery thereof and adapted to be acted upon by type selecting means through an intermediate means comprised of a plurality of push bars carried on the upper ends of a plurality of levers of the first order, on the lower ends of which are carried a plurality of selector arms having transverse heads provided thereon adapted to make contact with a plurality of selector bars; and the combination therewith of means for actuating type bars, timing means for consecutively releasing type bar actuating means, and a keyboard comprised of finger keys adapted to control the operation of type selecting means. 115

4. In a typewriting machine having key con-

- trolled means for selecting types to be actuated, means for registering type selections comprised of a plurality of slidable members carried in a revoluble member comprised of a plurality of 5 cylindrical sections, each of said sections being provided with a slot passing through the diameter thereof adapted to receive a slidable registering member, adapted to be operated upon by a type selecting means for the purpose of registering type selections for letters or letter combinations set up on the finger keys, said registering member being greater in length than the diameter of the cylindrical section, and provided with notches intermediate the ends thereof 10 adapted to cooperate with a spring detent, is at all times projected either forwardly or rearwardly beyond the periphery of the cylindrical section so as to form a lug thereon adapted to act upon a timing means for the purpose of distributing type selections to the type bar actuating means; and the combination therewith of means for actuating type bars, timing means for consecutively releasing type bar actuating means, and a keyboard comprised of finger keys adapted 15 to control the operation of type selecting means.
5. In a typewriting machine having means for actuating type bars and key controlled means for selecting type bars to be actuated, the combination of means for registering type selections comprised of slidable members projecting from the periphery of a revoluble member and forming lugs thereon adapted to be acted upon by a type selecting means and in turn to act upon a timing means for the purpose of distributing type 20 selections imparted thereto to a type bar actuating means, means for rotating the revoluble member for bringing lugs into contact with the timing means, comprised of a gear train and a one-round clutch running off of a motor drive shaft, means for resetting the slidable registering members comprised of a stationary member presenting a concave surface toward said revoluble member, the forward edge of said member being closer to the periphery of the revoluble 25 member than the rearward edge, and adapted to act upon the slidable registering members in such manner as to project them on the opposite side of the revoluble member so that when said member has completed one-half revolution all of said 30 registering members are projected rearwardly for the purpose of being further acted upon by the type selecting means, substantially as set forth.
6. In a typewriting machine embodying type bars and power means for actuating type bars, key controlled means for simultaneously selecting a multiplicity of type bars to be actuated and a timing means for releasing said actuating means for type bars selected in a consecutive order comprised of a series of plungers, there being one of said plungers provided for each type bar, said plungers ordinarily retained in primary position, means for tripping said plungers into secondary position, means for releasing said plungers from 35 secondary position comprised of a series of balls, there being sufficient space between said balls to allow the passage of only one of said plungers at a time, said plungers when in secondary position being adapted to rest upon and interlock with said balls in such way that the said tripped plungers will be released from secondary position by being allowed to pass between the said balls one at a time in a consecutive order, said 40 balls being displaced by the released plungers in a direction reverse to the line of consecution, the first of said tripped plungers in order of consecution serving to lock the balls to prevent their being displaced and allowing the passage of other plungers until it is withdrawn, which withdrawal releases the said balls and allows the next tripped plunger in order to displace the said balls and pass between them, each plunger as it is returned to primary position serving to release the balls and so effect the release of the next tripped plunger in order, means whereby the releasing of the said plungers from secondary position will release the type bar actuating means, and means whereby the said plungers are returned to primary position when the type bar actuation is completed, substantially as set forth. 45
7. In a typewriting machine embodying type bars and power means for actuating type bars, key controlled means for simultaneously selecting a multiplicity of type bars to be actuated and a timing means for releasing said actuating means for type bars selected in a consecutive order comprised of a series of plungers, there being one of said plungers provided for each type bar, said plungers ordinarily retained in primary position, means for tripping said plungers into secondary position, means for releasing said plungers from secondary position comprised of a series of rollers, there being sufficient space between said rollers to allow the passage of only one of said plungers at a time, said plungers when in secondary position being adapted to rest upon and interlock with said rollers in such way that the said tripped plungers will be released from secondary position by being allowed to pass between the said rollers one at a time in a consecutive order, said 50 rollers being displaced by the released plungers in a direction reverse to the line of consecution, the first of said tripped plungers in order of consecution serving to lock the rollers to prevent their being displaced and allowing the passage of other plungers until it is withdrawn, which withdrawal releases the said rollers and allows the next tripped plunger in order to displace the said rollers and pass between them, each plunger as it is returned to primary position serving to release the rollers and so effect the release of the next tripped plunger in order, means whereby the releasing of the said plungers from secondary position will release the type bar actuating means, and means whereby the said plungers are returned to primary position when the type bar actuation is completed, substantially as set forth. 55
8. In a typewriting machine having a platen and types, power means for operating type bars comprised of a continuously running power roller, a system of faced cams running off of said power roller, one cam for each type bar, said cams being provided with a flat portion on the periphery thereof for the purpose of breaking contact with the power roller and being normally held out of contact with said power roller, means constantly tending to throw said cam into contact with said power roller, means for restraining said cam for making contact with said power roller, means for releasing the restraining means, means for arresting the movement of the cam when it has completed one revolution, and means for connecting said cams to the type bars comprised of a crank pin carried on the face of said cam and a connecting arm carried thereon; and the combination therewith of means for selecting type bars to be operated, means for registering type selections, means for imparting type selections to actuating means, timing means for consecutively releasing actuating means, and a keyboard

comprised of finger keys adapted to control the operation of type selecting means.

9. In a typewriting machine having a platen and types, a system of reciprocating type bars 5 arcuately arrayed in two independent units and radiating from two independent writing centers in arcs struck in both vertical and horizontal planes from said writing centers, each of said type bars being provided with a guide slot formed 10 lengthwise thereof and means for engaging said guide slot, a system of type bar carriers pivotally mounted on their lower ends to sublinks carried on a system of type action hangers, the upper ends of said type bar carriers being connected to the forward ends of the type bars, a 15 system of guide links depending from said type action hangers and connected to said type bar carriers and adapted to coact with the type bar carriers and sublinks to give an approximate 20 straight line movement to the type bars, a system 25 of weighted toggles limited in their turning action about the toggle pivot by means of a slot with a pin working therein, said toggle forming a push link between the type bar actuating bell crank and the type bar carrier and adapted to 30 straighten out when the actuating means is in a maximum operated position and to carry the type bar into printing position, and a system of linkages connecting the type actions to the actuating means; and the combination therewith of 35 means for actuating type bars, key controlled means for selecting type bars to be actuated, means for registering type selections, means for imparting type selections to actuating means, and a keyboard comprised of finger keys adapted to 40 control the operation of type selecting means.

10. In a typewriting machine having a platen and types, a type basket vertically and centrally divided, comprised of two independent units, one 45 of said units being fixedly mounted and comprised of an array of type bars radiating in both vertical and horizontal arcs from a fixed writing center; and the combination therewith of means for operating the type bars, key controlled means for 50 selecting types to be actuated, means for registering type selections, means for imparting type selections to an actuating means, and a timing means for consecutively releasing the actuating means, and a keyboard comprised of finger keys adapted to 55 control the operation of the type selecting means.

11. In a typewriting machine having a platen and types, a type basket vertically and centrally divided, comprised of two independent units, one 55 of said units being movably mounted, movable in a parallel direction to platen and comprised of an array of type bars radiating in both vertical and horizontal arcs struck from a writing center movable with said unit; and the combination 60 therewith of means for operating the type bars, key controlled means for selecting types to be actuated, means for registering type selections, means for imparting type selections to an actuating means, and a timing means for consecutively 65 releasing the actuating means, and a keyboard comprised of finger keys adapted to control the operation of the type selecting means.

12. In a typewriting machine having a platen and types, a type basket comprised of two independent units, one of said units being fixedly mounted and the other movably mounted and comprised of an array of type bars radiating in

both vertical and horizontal arcs struck from two independent writing centers, means for spacing said movable unit consisting of wedge shaped plungers passing between spacing blocks slidably mounted and movable in a parallel direction to 80 the platen, the difference in the thickness of the two ends of said wedge shaped plungers being equal to one letter space, means for forcing said wedge shaped plungers between said slideable spacing blocks, and connecting means for imparting spacing movement to said movable type basket unit, substantially as set forth; and the combination of means for operating the type bars, key controlled means for selecting types to be actuated, means for registering type selections, means for imparting type selections to actuating means, timing means for consecutively releasing actuating means, and a keyboard comprised of finger keys adapted to control the operation of type selecting means. 85

13. In a typewriting machine having a platen and types, a type basket comprised of two independent units, one of said units being fixedly mounted and the other movably mounted and comprised of an array of type bars radiating in both vertical and horizontal arcs struck from two independent writing centers, means for spacing said movable unit consisting of wedge shaped plungers passing between spacing blocks slidably mounted and movable in a parallel direction to the platen, the difference in the thickness of the two ends of said wedge shaped plungers being equal to one letter space, means for forcing said wedge shaped plungers between the slideable spacing blocks comprising a series 100 of plungers adapted to be acted upon by power means, means connecting said plungers to the wedge shaped plungers, means for returning the wedge shaped plungers to normal position; and the combination of means for operating the type bars, key controlled means for selecting types to be actuated, means for registering type selections, means for imparting type selections to actuating means, and a keyboard comprised of finger keys adapted to 105 control the operation of type selecting means. 110

14. In a typewriting machine having a platen and typebars, in combination a type basket com-

prised of two independent units, one of said units being fixedly mounted and the other movably mounted, means for spacing said movable unit in a direction parallel to the platen, means for locking the movable unit in a spaced position, means for releasing the locking means when 115 type operations in the movable unit have been completed, means for returning the movable unit to normal position, means for engaging the platen carriage and moving it with the movable unit when said unit is returned to normal position, for the purpose of positioning the platen for further type actions, substantially as set forth; and means for operating the type bars, key controlled means for selecting types to be 120 actuated, means for registering type selections, means for imparting type selections to actuating means, timing means for consecutively releasing actuating means, and a keyboard comprised of finger keys adapted to control the 125 operation of type selecting means. 130

15. In a typewriting machine having a platen and typebars, in combination a type basket com-

prised of two independent units, one of said units being fixedly mounted and the other movably mounted, means for spacing said movable unit in a direction parallel to the platen, means for locking the movable unit in a spaced position, means for releasing the locking means when type operations in the movable unit have been completed, means for returning the movable unit to normal position, means for engaging the platen carriage and moving it with the movable unit when said unit is returned to normal position, for the purpose of positioning the platen for further type actions, substantially as set forth; and means for operating the type bars, key controlled means for selecting types to be actuated, means for registering type selections, means for imparting type selections to actuating means, timing means for consecutively releasing actuating means, and a keyboard comprised of finger keys adapted to control the operation of type selecting means. 140
